UNITED STATES PATENT OFFICE.

MILES CONNOR, OF PUEBLO, COLORADO.

HYDROCARBON-FURNACE.

1,069,230.

Specification of Letters Patent. Patented Aug. 5, 1913.

Application filed December 27, 1909. Serial No. 534,981.

To all whom it may concern:

Be it known that I, MILES CONNOR, a citizen of the United States, residing at Pueblo, in the county of Pueblo and State 5 of Colorado, have invented a certain new and useful Improvement in Hydrocarbon-Furnaces, of which the following is a full, clear, and exact description.

My invention is an improvement in hydro- 10 carbon furnaces and, while of general applicability, it is especially adapted for use in circular boilers of the vertical type and particularly in fire-engine boilers.

The principal object of my invention is 15 to provide a grate for circular vertical boilers for which oil is to be the principal fuel, which grate will allow the use of wood or other fixed carbon fuel for initially generating steam and at the same time to make the 20 entire grate area available so as not to interfere with the prompt generating of steam when using wood or other similar fuels.

A further object of my invention is to so 25 design the grate as to cause the products of combustion to take a rotary, vortex or spiral motion in their course from the grate, especially where forced draft is used as in steam fire-engine service. By means of this 30 rotary or spiral course taken by the upwardly passing products of combustion, I secure an even distribution of heat throughout 35 the boiler and more complete combustion of the fuel than is possible with the ordinary brick arrangement for burning liquid fuel.

It will be evident that in an attempt to 40 burn oil in a small, circular fire-box, especially when forced draft is used, the heat of combustion is apt to be concentrated on a particular part of the fire-box or boiler and damage and inefficiency result. To obviate this it has been customary to protect the fire-box or other parts of the furnace by fire-brick or other insulating material. In 45 special service where the units are detached, as in fire-engine service, bricking up the fire-box would be objectionable as it would not provide grate area for generating steam to operate the atomizer; and, furthermore, it 50 would be a hard matter to place brick in such a fire-box that it would stand the requirements of the service, such as jolting over rough roads.

These and other objects and advantages of 55 my invention which will later appear in the specification I attain by the construction

shown in the accompanying drawings in which—

Figure 1 is a central vertical section of a boiler and furnace with my invention in position; Fig. 2 is a partial plan view of a grate in which the slots radiate from the center; Fig. 3 is a partial section of a grate showing the inclination of the slots; and Fig. 4 is a partial plan view of a modified 65 form of grate.

In the drawings 1 represents a boiler and 70 2 a steam pipe leading from the boiler to the liquid fuel supply tank 4; 3 is a valve in the pipe 2. Flow of oil from the tank 4 is controlled by the valve 5. 6 is a by-pass leading steam to the atomizer 8 and 7 is a valve in the by-pass for controlling the delivery of steam to the atomizer. A valve 10 is also placed in the steam pipe for regulating the 75 admission of steam to the tank 4. These portions of the device are old in the art and are merely shown for the purpose of illustrating how my device is to be employed.

The atomized fuel enters the furnace 80 through pipe 9 and is discharged from the nozzle 11. Below the fuel discharge nozzle is placed the grate 14 and this grate is provided with slotted openings which are so inclined as to give a spiral direction to the air 85 which passes through them and consequently to the products formed by the combustion of the liquid fuel by this air. In the form of grate shown in Fig. 2 the slots radiate from the center and all are inclined 90 upwardly in a counter-clockwise direction, giving to the products of combustion the direction indicated by the flame lines in Fig. 2. In the form of grate shown in Fig. 4, the slots 14^a are inclined in one direction with 95 relation to the vertical and the slots 14^b are inclined in the opposite direction; this will tend to cause the gases above the grate sections to travel in opposite directions and the resultant action will be a rotary or spiral motion of the gases. In Fig. 3 the inclination of the slots, which are designated by the numeral 15, is clearly shown.

I prefer to employ a heat insulating ring 100 12 to protect the water legs of the boiler and to retain heat for aiding combustion, but this may be omitted without departing from my invention.

The manner of use of my device is as follows: A starting fire of wood or wood and 11 coal or the like, having been laid on the grate, it is ignited and allowed to burn until

- a sufficient head of steam is generated to operate the oil feed. Then the oil is turned on and, the ash left by the starting fire being inconsiderable and not sufficient to close the 5 grate bar openings, the air passes up through the grate slots and impinging against the entering oil spray directs it in a spiral direction, or, in other words, in a vortex. Aside from the great advantage of 10 preventing the concentration of the heat at any one spot this rotary action causes the gas and air to be more thoroughly commingled and retains the mixture longer in the fire-box, to the end that combustion is more 15 complete—thus performing the function of a fire-brick baffle or honey-comb.
- Having thus described my invention, what I claim and desire to secure by Letters Patent is:
- 20 1. In a hydro-carbon furnace, a hydro-carbon injector or nozzle and a grate located below said injector, said grate having air passages therethrough so disposed as to give

a vortex motion to the body of gases above the grate. 25

2. In a hydro-carbon furnace, a hydro-carbon injector or nozzle and a grate located below said injector, said grate having air passages therein so disposed with relation to the vertical as to give a spiral or rotary direction to the air passing therethrough and to the resulting products of combustion. 30

3. In a hydro-carbon furnace of circular form, a hydro-carbon injector arranged to discharge in a direction tangentially of the 35 furnace and a grate located below said injector, said grate having air passages therein disposed at an angle to the vertical and inclined to discharge the air in the same tangential direction as the injector discharges 40 the fuel.

MILES CONNOR.
